UNITED STATES PATENT OFFICE.

WALTER P. NEUBERT, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

PLUNGER LOCK WITH CIRCUIT CONTROLLER FOR RAILWAY SWITCHES.

Application filed August 29, 1922. Serial No. 585,033.

To all whom it may concern:

Be it known that I, WALTER P. NEUBERT, a citizen of the United States, residing at Pittsburgh, in the county of Allegheny and 5 State of Pennsylvania, have invented certain new and useful Improvements in Plunger Locks with Circuit Controllers for Railway Switches, of which the following is a specification.

10 My invention relates to plunger locks for railway switches and to circuit controllers operated by such locks.

I will describe one form of apparatus embodying my invention, and will then point 15 out the novel features thereof in claims.

In the accompanying drawings, Fig. 1 is a view showing in vertical longitudinal section one form of apparatus embodying my invention. Fig. 2 is a top plan view of the 20 apparatus shown in Fig. 1. Fig. 3 is a vertical sectional view on the line III—III of Fig. 1. Fig. 4 is a vertical sectional view on the line IV—IV of Fig. 1. Fig. 5 is a left-hand end view of the apparatus shown in 25 Fig. 1.

Similar reference characters refer to similar parts in each of the several views.

Referring to the drawings, the apparatus 30 comprises a casing A having a tail-like projection A'. The main body of the casing A is provided with a cover B connected with the casing by hinges 2 and 2^a, and the tail-like projection A' is provided with a removable cover B', which is attached thereto by machine screws 3.

The cover plate B' is provided with a rectangular slot 21, as best shown in Fig. 5, and this slot constitutes a guide for a plunger P, which slides on the upper surface of the 40 projection A'. The projection A' of the enclosing casing is provided with a transverse slot 24 to accommodate a lock rod L, which is attached to a railway switch. The upper surface of the lock rod L is provided with notches 25 to accommodate the plunger P.

As shown in Figs. 1 and 2, the plunger P is in its projected or locking position, and when in this position it passes through one 45 of the notches 25 in the lock rod L. When the parts are in these positions the railway switch is locked in either its normal or its reverse position. In order to move the switch the plunger P must be retracted to its

unlocking position; that is, to such position 55 that the right-hand end of this plunger, as viewed in Fig. 1, clears the lock rod L. The switch may then be shifted to its other position, thus bringing another notch 25 in the lock rod L into register with the plunger 60 P. The plunger is then restored to its projected position so that the switch is locked.

The reference character R designates a rocker arm which is pivotally mounted intermediate its ends on a pin 4, which in turn 65 is supported in the casing A in the manner best shown in Fig. 4. Referring to this view, it will be seen that the pin is located in suitable holes 5^a in the walls of the casing. The outer ends of these holes are enlarged and 70 are tapped to receive pipe plugs 5, the functions of which are to hold the pin 4 in proper position in the holes 5^a. The rocker arm R carries two rollers 8 and 9 journaled in suitable manner in this arm so as to be free to 75 rotate with respect to the arm. These rollers co-act with the plunger P, and for this purpose the under surface of the plunger is provided with a recess 6 and the inner end of the plunger is chamfered at 7, as shown in 80 Fig. 1.

When the plunger P is in the projected or locking position, roller 8 is located in the recess 6, whereas roller 9 engages with an unrecessed portion 6^a of the under surface of 85 the plunger. The arm R is then rocked to its extreme position in clockwise direction as viewed in Fig. 1. When the plunger P is withdrawn to the unlocking position, roller 9 is first released by the inner end 7 of 90 the plunger, and subsequently roller 8 rides out of the recess 6 and onto the unrecessed surface 6^a of the plunger, so that the rocker arm R is shifted in counter-clockwise direction from the position in which it is shown 95 in Fig. 1. When the plunger P is restored to its locking position, the rocker arm is, of course, restored to the position shown in the drawing. It will be seen, therefore, that when the plunger is in locking position, the 100 right-hand end of the rocker arm R is down and that when the plunger is in the unlocking position, the right-hand end of arm R is elevated.

Referring now particularly to Figs. 1 and 105 3, the right-hand end of arm R is drilled to receive a pin 10, which pin also passes through suitable holes in the two legs 11^a

of a block 11. This block 11 is mounted to slide vertically on studs 17, which are fixed in the casing A and which studs pass freely through holes 18 in the block 11. The block 5 is biased to an elevated position by springs 16 surrounding the studs 17, and the upward movement of the block is limited by screws 19 which are adjustably mounted in lugs 20 projecting inwardly from the casing A.

10 The block 11 actuates a circuit controller C comprising two contact fingers 14 and 15, which are mounted in a block 22 of insulating material, and which block is in turn supported by lugs 23 projecting inwardly 15 from the casing A. The upper contact finger 15 is fixed and is comparatively rigid, whereas the lower contact finger 14 is comparatively flexible and is extended to pass between two blocks 12 and 13 of insulating 20 material mounted on the block 11 and attached thereto by screws 26.

The parts are so designed and adjusted that when the plunger P is in the projected or locking position, as shown in Fig. 1, the 25 block 11 is forced downwardly against the action of the springs 16 so that contact 14-15 is opened. When the plunger P is withdrawn or retracted to its unlocking position, the block 11 is released as soon as the 30 right-hand end 7 clears the roller 9, whereupon this block rises due to the action of springs 16 and contact 14-15 becomes closed. Upon a slight further movement of the plunger P the roller 8 passes out of the recess 35 6, thereby positively locking the block 11 in elevated position.

The circuit controller C may comprise any suitable number of sets of contact springs 14-15, two such sets being shown in Figs. 40 2 and 3.

Although I have herein shown and described only one form of apparatus embodying my invention, it is understood that various changes and modifications may be 45 made therein within the scope of the appended claims without departing from the spirit and scope of my invention.

Having thus described my invention, what I claim is:

50 1. In combination, a casing provided with a rectangular slot, a rectangular plunger mounted to reciprocate in said slot and adapted for co-operation with a railway switch lock rod, said plunger having a recess in its under surface, a rocker arm pivotally mounted beneath said plunger and having two rollers co-operating with the plunger in such manner that when the plunger is

projected into locking position one roller occupies said recess and the other roller coacts with an unrecessed point on the under surface of the plunger, whereas when the plunger is retracted to unlocking position the first roller engages an unrecessed point on the under surface of the plunger and the second roller is free from the inner end of the plunger, means for biasing said rocker arm in such direction that said second roller rises when freed from the inner end of the plunger, and a circuit controller located in 70 said casing and operated by said rocker arm.

2. In combination, a casing provided with a rectangular slot, a rectangular plunger mounted to reciprocate in said slot and adapted for co-operation with a railway 75 switch lock rod, said plunger having a recess in its under surface, a rocker arm pivotally mounted beneath said plunger and having two rollers co-operating with the plunger in such manner that when the plunger is projected into locking position one roller occupies said recess and the other roller coacts with an unrecessed point on the under surface of the plunger, whereas when the plunger is retracted to unlocking position the first roller engages an unrecessed point on the under surface of the plunger and the second roller is free from the inner end of the plunger, and a circuit controller located in 80 said casing and operated by said rocker arm.

3. In combination, a casing having a tail-like extension, a detachable cover for said extension provided with a rectangular slot in its under surface, a rectangular plunger mounted to reciprocate in said slot and adapted for co-operation with a railway switch lock rod, said plunger having a recess in its under surface, a rocker arm pivotally mounted beneath said plunger and having two rollers cooperating with the plunger in such manner that when the plunger is projected into locking position one roller occupies said recess and the other roller coacts with an unrecessed point on the 95 under surface of the plunger, whereas when the plunger is retracted to unlocking position the first roller engages an unrecessed point on the under surface of the plunger and the second roller is free from the inner end of the plunger, and a circuit controller located in 100 said casing and operated by said rocker arm.

In testimony whereof I affix my signature.

WALTER P. NEUBERT.
